FIREPLACE GRATE OR THE LIKE

Edward Foreman, 11018 Acalanes Drive, and De Moody
Blair, 303 Darr St., both of Oakland, Calif. 94603

Filed Sept. 23, 1965, Ser. No. 87,127

Term of patent 14 years

(Cl. D81—5)

We claim:

The ornamental design for a fireplace grate or the like, as shown and described.
